SCREEN DOOR CHECK AND SILENCER

James H. Boye, Chicago, Ill., assignor to James H. Boye Manufacturing Company, Chicago, Ill., a corporation of Illinois

Application January 15, 1948, Serial No. 2,450

2 Claims. (Cl. 292—73)

1

The invention relates to door closing devices and has reference more particularly to a device for use on screen doors which are generally closed by a coil spring, the device checking the closing action of the door and also closing the door in a manner to substantially eliminate the noise and jar which would otherwise take place.

An object of the invention is to provide a device for checking the closing action of a screen door or the like and which will silence the closing action by cushioning the door as it closes and also apply tension to hold the door closed.

Another object resides in the provision of an improved door closer and silencer wherein the silencer works in conjunction with the closer, employing the same parts and which therefore have a dual function, operating first to cushion the closing of the door and then to releasably hold the door closed.

Another object of the invention is to provide a door closer and silencer which will employ rubber rollers having coaction in a unique manner to perform the desired operations of first cushioning the slam of the door to thus substantially silence the closing action, and then holding the door closed thus preventing rebound.

Another object of the invention resides in the provision of a device comprising essentially a pair of rubber rollers having coaction for the purposes described, and wherein one roller is fixedly secured to the door jamb and the other roller is secured to the frame of the door so as to have movement therewith.

With these and various other objects in view, the invention may consist of certain novel features of construction and operation as will be more fully described and particularly pointed out in the specification, drawings and claims appended hereto.

In the drawings which illustrate an embodiment of the invention and wherein like reference characters are used to designate like parts—

Figure 1 is an elevational view with parts in section showing the device of the invention applied to the screen door;

Figure 2 is a horizontal sectional view taken substantially along line 2—2 of Figure 1 and showing the present door closer and silencer in plan;

Figure 3 is a vertical sectional view taken along line 3—3 of Figure 2;

Figure 4 is a vertical sectional view taken along line 4—4 of Figure 3;

Figure 5 is a perspective view illustrating the

2

initial contact of the rollers for silencing the closing action of the door; and

Figure 6 is a side elevational view of the present device.

Referring to the drawings, and more particularly Figures 1 and 5, the embodiment selected for illustrating the invention essentially consists of a bracket 10 journaling a rubber roller 11, the bracket being suitably fixed to the door jamb 12 and a second bracket 13 journaling the rubber roller 14, said second bracket being fixedly secured to the frame 15 of the door and thus the rubber roller 14 has bodily movement with respect to the roller 11. The device of the invention has been particularly designed for application to screen doors as illustrated in Figure 1, such doors generally comprising a frame as 15, extending around the periphery of the door and which may be braced and reinforced by one or more horizontal cross pieces 16. The door 15 is suitably mounted for opening and closing movements by the hinges 17 which are secured to frame 15 of the door and to the door jamb generally indicated by numeral 12. Screen doors of this type are tensioned in a closing direction by a coil spring, such as 18, secured at one end to the door jamb and at its other end to the cross piece 16 at a point intermediate its length. Such springs not only cause the screen door to close against the jamb but also apply tension to hold the door closed, thus preventing flies and other insects from entering the house. However, the action of the coil spring in closing the door is so forceful and direct as to cause considerable jar as the door slams against the jamb. Not only is the jar objectionable but the noise incidental thereto is likewise objectionable and disturbing.

The device of the invention provides coacting rubber rollers 11 and 14, one being mounted on the door jamb and the other on the movable frame of the door for checking the closing action in a manner to silence the same and which will thereafter releasably hold the door closed and also prevent rebound of the door in an opening direction.

The bracket generally indicated 10 is substantially U-shaped, having securing flanges 20 secured to the door jamb 12 by the screws 21, and a center portion 22 to which the rubber roller 11 is rotatably secured by means of the screw 23. The screw is threaded in portion 22, Figure 3, and is locked in adjusted position by nut 24. The roller 11 carries the metal sleeve 25 of a length just slightly less than the width of the roller so that the outer disc 26 will act as a

friction brake. The disc 26 is mounted on screw 23 between the roller and the head of the screw and the braking effect of the disc can be adjusted by screwing 23 inwardly or outwardly. It is desirable for the roller 11 to be rotatable on the screw 23. However, in order to check the closing action of the screen door said roller 11 can not rotate freely but considerable braking action must be applied thereto by the disc 26 so that it will rotate to a slight extent and then only upon substantial impact as a result of engagement therewith of roller 14.

Said roller 14 is carried by bracket 13 having a securing flange 28 and depending ears 30. The bracket is suitably fixed to the frame 15 of the door by securing screws 31 which have location in slots 32 whereby the bracket can be adjusted vertically for adjusting the contact of roller 14 with roller 11 to secure the desired checking of the screen door when the rollers engage. The depending ears 30 are apertured for receiving the screw 33, Figure 3, which at its right hand end is threaded to the bracket with its projecting end having threaded thereto the wing nut 34 for locking the screw in adjusted position. The roller 14 is journaled on the screw 33 by the headed sleeve 35 and the washer 36 is provided for applying variable tension to the roller whereby said washer regulates the braking effect on roller 14 in much the same manner as disc 26 regulates the braking effect of roller 11. The screw 33 carries at its left end the coil spring 37 which is confined between the head of the screw and the collar 38, said collar having free contact with the washer 36 and applying thereto the tension exerted by coil spring 37. The ear 30 is apertured for receiving the collar 38 which is thus held by the bracket 13 and centered for journaling the screw 33.

In application of the present device the bracket 10 is suitably secured to jamb 12, as illustrated in Figure 1, at a point approximately midway of the upper half of the door. The bracket 13 is secured to the frame 15 of the door and the vertical positioning of the bracket is such that the rubber roller 14 will contact rubber roller 11 as the screen door closes against the door jamb. To facilitate the proper positioning of bracket 13 the flange 28 of said bracket is provided with slots 32. The positioning of rubber roller 14 with respect to roller 11 is somewhat critical since proper functioning of the device requires that roller 14 contact rubber roller 11 so as to have a compressing action therewith. This compressing action will be clearly understood by comparing the position of the rollers in Figures 4 and 5. When the rollers contact, as shown in Figure 5, the slam of the door is cushioned by the rollers since they are made of resilient material and also the closing action of the door is materially silenced. If the initial adjustment of bracket 13 does not provide for proper contact of the rollers for silencing and cushioning the jar as the door closes it is only necessary to loosen up on screws 31 and adjust the bracket until proper contact results.

For proper closing action of the door and operation of the parts to prevent rebound it is also necessary that the disc 26 and washer 36 have adequate tension applied thereto for braking the rollers. By adjustment of screw 23 the proper braking effect can be obtained for the roller 11 and the braking action on roller 14 can be adjusted by manipulation of screw 33. When roller 14 passes over the high point with respect to roller

11, the rollers should rotate on their respective axes, thereby facilitating the final closing movement of the door. When the parts assume the position as shown in Figure 4, the screen door is completely closed and it will be observed that the same is held closed by the contact which roller 14 has with roller 11. This may be described as a locking position for roller 14 since the same is beyond dead center as regards roller 11. This action which the rollers have with each other not only releasably holds the door closed but prevents rebound of the door.

The action of the present device in preventing rebound is very desirable and comprises one of the important functions of the device, the function resulting from coaction of the same parts which also cushion the closing of the door and silence the closing action. When roller 14 passes over the high point of roller 11 the resilient material of the rollers is compressed which results in the rotative movement of the rollers as described and cushioning of the closing action of the door. When the rollers assume the position as shown in Figure 4 they are no longer compressed but their peripheries are fully expanded to original position. Since considerable force is required to compress the material of the rollers the door is held closed and any rebound action is absorbed by the rollers.

The invention is not to be limited to or by details of construction of the particular embodiment thereof illustrated by the drawings as various forms of the device will of course be apparent to those skilled in the art without departing from the spirit of the invention or the scope of the claims.

What is claimed is:

1. In a door check and silencer for a door jamb and a door hingedly mounted for opening and closing movements therewith, in combination, a bracket fixedly secured to the jamb, a roller journaled by the bracket, adjustable means for tensioning the roller to prevent free rotation, a second bracket providing spaced depending ears, a roller located between said ears and journaled by a screw, said second bracket being fixedly secured to the door in a position whereby the rollers contact each other as the door closes and have a compressing action to check the closing of the door and to silence the same, said screw having threaded engagement with one ear and projecting beyond both ears, resilient means retained by one of the projecting ends of the screw for applying tension to the said roller journaled between the ears, and a wing nut threaded to the other projecting end of said screw for locking the screw in adjusted position.

2. In a door check and silencer for a door jamb and a door hingedly mounted for opening and closing movements therewith, in combination, a bracket for securement to the door jamb having a center portion, a shaft adjustably secured to the center portion and projecting outwardly therefrom, a resilient roller journaled by said shaft, a second bracket providing spaced depending ears, a roller located between said ears and journaled by a screw, said second bracket being fixedly secured to the door in a position whereby the rollers contact each other as the door closes and have a compressing action to check the closing of the door and to silence the same, said screw having threaded engagement with one and projecting beyond both ears, resilient means retained by one of the projecting ends of the screw for applying tension to the said roller journaled

between the ears, and a wing nut threaded to the other projecting end of said screw for locking the screw in adjusted position.
